UNITED STATES PATENT OFFICE.

ADOLF STEFFEN, OF PITTSBURGH, PENNSYLVANIA, ASSIGNOR TO ADAMS BROTHERS MANUFACTURING COMPANY, A CORPORATION OF PENNSYLVANIA.

GAS BURNER.

Application filed April 9, 1925. Serial No. 21,817.

My invention relates to gas heating devices and particularly to gas burners for air heaters.

One object of my invention is to provide a gas burner assembly that shall ensure a proper and even distribution of a gaseous mixture to a plurality of burner nozzles associated therewith.

Another object of my invention is to provide a burner nozzle of an improved construction that shall be highly efficient, easily manufactured and installed, and noiseless in operation.

In practicing my invention I provide an intake pipe, an elongated receiving chamber connected thereto, having a plurality of burner nozzles thereon, and having depending and integral flange members therein for ensuring a substantially even distribution of gas to the nozzles. Each of the burner nozzles embodies a relatively small, removable tubular member having a plurality of relatively narrow, deep and short, radial slits therein.

25 In the single sheet of drawings,

Figure 1 is a view, in side elevation, of a device embodying my invention.

Fig. 2 is an end view of a receiving chamber embodying my invention.

30 Fig. 3 is a view, in lateral section therethrough, taken on the line III—III of Fig. 1,

Fig. 4 is a view, in lateral section therethrough, taken on the line IV—IV of Fig. 1,

Fig. 5 is a top plan view of a burner nozzle embodying my invention, and

Fig. 6 is a view, in side elevation thereof.

An intake pipe 11 has an opening at one end thereof, designated by the numeral 12, for the admission of air, and a tubular inlet 13 having the usual needle valve 14 therein to regulate the amount of gas admitted.

The intake pipe 11 is provided with a lateral extension 15 that extends substantially at right angles to the main body of the intake pipe and is provided with a socket or seat 16 to receive one end of a receiving chamber 17. The receiving chamber 17 is substantially rectangular in lateral section but has a lesser width at the top portion than at the bottom portion and is narrower at the outer end than at that end fitting into the extension 15. It is relatively long and has a plurality of substantially circular openings 18 in the top wall thereof, which openings are symmetrically spaced from each

other over substantially the entire length of the member 17. Any suitable or desired means may be employed to hold one end of the member 17 within the seat 16 in the extension 15.

I prefer to make the member 17 of cast iron, and also to make it initially with an open bottom but with a shoulder 19 and 21 at the bottom edge of each of the side walls and to close the chamber by a plate 22 that is suitably secured thereagainst as by brazing or welding. The member 11 is preferably provided with an integral supporting lug 23 that is adapted to abut against the member 22 and to thereby support the receiving chamber 17.

The gas burner is particularly adapted for use in gas heaters of the open radiant type, comprising a plurality of vertically extending tubular clay radiants that are heated by the burning gas and become luminous. Such gas heaters usually embody an ornamental casing and the assembly illustrated in Fig. 1 of the drawing is located in the bottom portion thereof with substantially all of the parts hidden from view. I prefer to employ an intake pipe of the kind illustrated and to mount the receiving chamber immediately thereabove whereby the gaseous mixture is caused to enter the relatively long receiving chamber 17 at one end thereof.

Means for effecting a uniform distribution of the gaseous mixture entering the receiving chamber to all of the openings 18 and of the burner nozzles located therein and to be hereinafter described in detail, comprises an integral vertically depending flange member or baffle 24 that is located at the entering end of the receiving chamber. The flange 24 comprises a relatively long intermediate portion and two shorter side portions as is illustrated more particularly in Fig. 2 of the drawings. When the gaseous mixture enters the intake pipe and flows therethrough it will tend to flow toward the upper portion of the part 15 and if permitted to flow freely into the receiving chamber 17, a disproportionately large amount thereof would flow out through the first few burners adjacent to the entering end of the chamber. The intermediate portion of the flange 24 causes a diversion of the gaseous mixture downwardly against the bottom member 22 and thereby prevents too much

of the mixture flowing out through the burner nozzles adjacent to the entering end. The relatively shorter lateral portions of the flange member 24 permit the gaseous mixture to flow along the inside of the two walls of the chamber, an effect that is assisted by making the outer end of the chamber 17 relatively narrower than the entering end as hereinbefore described and as 10 more particularly shown in Fig. 2 of the drawings.

A vertically depending lug 25 integral with the top wall of the receiving chamber is located between the first and second openings adjacent to the entering end of the chamber, and prevents an unduly large proportion of the gaseous mixture flowing out through and being burnt in the second burner nozzle. However, I have found that a 15 depending flange such as hereinbefore described having a relatively long central portion and two shorter side portions is effective by itself to ensure a substantially uniform distribution of the gaseous mixture to 20 all of the burner nozzles located on such a receiving chamber.

A plurality of burner nozzles 26 is located in the respective openings 18 and severally comprise a tubular metal member having 30 an outer annular flange 27 therearound in order to support the same on and in interfitting relation with the upper wall of the chamber 17. The internal diameter of the lower portion of the nozzle 26 is relatively 35 large so that the thickness of the wall 28 is relatively small. The upper portion of the burner nozzle has a smaller internal diameter than the lower portion, as may be noted from Fig. 5 of the drawings, and the relatively thick wall 29 is provided with a plurality of relatively narrow, radially-extending slits 31 that are symmetrically spaced peripherally thereof. The slits 31 are relatively narrow, deep, and short, the latter dimension being the radial one. The depth of 40 the slits in the portion 29 is relatively large as may be noted from the sectional view illustrated in Fig. 4 of the drawings.

An auxiliary air tube 32 is provided for 50 each of the burner nozzles 26 and has the bottom portion thereof extending through suitable openings 33 in the member 22, while the upper end thereof is located within the portion 29 of the burner nozzle within 55 which it fits relatively closely.

The burner nozzles 26 may each be provided with one or a plurality of symmetrically spaced integral lugs 34 on the outside surfaces thereof. The lugs 34 serve to support a metal plate (not shown) upon which the hereinbefore mentioned clay radiants are supported in the gas heater frame or casing, the weight of these parts serving to hold the burner nozzles tightly against the 60 upper surface of the chamber 17.

The closed outer end of the chamber 17 may be provided with an integral portion 35 that may be a part of the member 22 or that may be a part of the member 17, in order to permit of supporting the receiving chamber 70 from a suitable metal cross bar 36, a short machine screw 37 being employed to hold the two members together.

As was hereinbefore noted, it is believed that the gaseous mixture is caused to flow 75 along the inside surface of the side walls of the receiving chamber by reason of the shape of the depending flange 24 and this construction is particularly effective when considering the location of the auxiliary air 80 tubes 32 which are in the central portion of the chamber 17. I have found it possible to light the gaseous mixture when the needle valve 14 has once been properly adjusted without any "flare back" or any tendency toward 85 an explosive action, irrespective of the amount of gaseous mixture that is admitted to the intake pipe and to the receiving chamber. I have also found that the burner nozzles operate noiselessly even when a 90 relatively high gas pressure is present, and I attribute this operation to the relatively 95 large number of radial slits that are relatively short in the radial direction, but are relatively deep as compared to the width thereof. I believe also, that the auxiliary air tube provided for each of the burner nozzles aids in securing this effect.

While I have illustrated a receiving chamber into which the gaseous mixture is admitted at one end, it is easily possible to adapt my invention to a receiving chamber into which the gaseous mixture enters at a point intermediate its ends, and the provision of the depending flanges 24 in the path 100 of the incoming gaseous mixture will effect the proper distribution thereof to all of the burner nozzles.

Various modifications may be made in the device embodying my invention without departing from the spirit and scope thereof, and it is intended that all such modifications shall be included in the appended 110 claims which are to be limited only by the prior art.

I claim as my invention:—

1. In a burner assembly for gas heaters, the combination with an intake pipe, and a receiving chamber connected therewith and having a plurality of burner nozzles thereon, of a vertical baffle located adjacent to the entrance of said receiving chamber for effecting uniform distribution of a gaseous mixture to said nozzles, and a vertically depending lug in the chamber, between the 120 first two burners.

2. In a gas burner assembly, the combination with an intake pipe, and an elongated receiving chamber connected therewith and having a plurality of aligned burner nozzles 125 130

thereon, of a vertically depending flange deeper at its center than at its sides at the entrance of said receiving chamber for effecting substantially uniform distribution 5 of a gaseous mixture to said nozzles.

3. In a gas burner assembly, the combination with an intake pipe and an elongated receiving chamber connected therewith and having a plurality of alined burner nozzles 10 thereon, of a laterally-extending flange, integral with said receiving chamber and having a relatively long intermediate portion and two shorter side portions extending into the path of flow of a gaseous mixture at the 15 entrance thereof into the receiving chamber, for effecting substantially uniform distribution of a gaseous mixture to said nozzles.

4. In a gas burner assembly, the combination with an elongated receiving chamber, 20 of a plurality of burner nozzles located thereon, each comprising a plurality of relatively narrow, deep and short radial slits for permitting a gaseous mixture to flow therethrough and be burned thereon, an air 25 passage at the center of each nozzle, said slits communicating directly with the top of said passage.

5. In a gas burner assembly, the combination with an elongated relatively narrow receiving chamber, of a plurality of tubular 30 burner nozzles located thereon in alined spaced relation, each having a plurality of radially-extending, relatively deep slits therein for permitting a gaseous mixture to 35 flow therethrough, an auxiliary air tube ex-

tending into the opening inside of said slits, and means integral with said receiving chamber and located at the entrance portion thereof in the path of the incoming gaseous mixture for effecting substantially uniform 40 distribution of the gaseous mixture to said burner nozzles.

6. In a gas burner assembly, comprising in combination, an elongated receiving chamber having a plurality of openings in 45 its top wall, a tubular burner nozzle positioned in each of said openings and communicating directly with said chamber, each nozzle comprising a plurality of relatively narrow, deep and short radial slits for permitting a gaseous mixture to flow therethrough, and an auxiliary air tube extending 50 into the tubular opening inside of said slits.

7. In a gas burner assembly, the combination with a receiving chamber, of a burner nozzle having a tubular opening in its center located thereon, said nozzle having a plurality of relatively narrow, deep and short radial slits for permitting a gaseous 55 mixture to flow therethrough and be burned thereon, and an air tube extending into the bottom of said tubular opening, said slits having direct communication with the top 60 of said opening.

In testimony whereof, I have hereunto subscribed my name this fourth day of April, 1925.

ADOLF STEFFEN.
